UNITED STATES PATENT OFFICE.

LÉON M. E. ROTTENBURG, OF IXELLES-BRUSSELS, BELGIUM.

RACE GAME.

Application filed April 20, 1927, Serial No. 185,363, and in Belgium November 5, 1926.

The present invention relates to appliances for a race game to be played indoors, of the kind wherein miniature horses are moved over a divided and numbered chart representing a race course, the moves being determined by chance.

The game to be played has for its object: (1) to realize at home in a complete and perfect manner, the imitation of horse-races in all their details, varieties and events, so as to afford the illusion that the game is played by means of actual horses, mounted by actual jockeys and moving upon a real race-track; (2) to obtain a constant and compact group 15 of the competitors during the time of a competition, so that each of them retains up to the end a chance of winning; (3) to divide the competitors by expertness such as in actual races, so that the spectators can mathematically state the chances of each competitor.

The invention consists in a material imitation at a suitable scale of all the accessories and installations of an actual race course, use 25 being made of special dice described herein-after, which allow the application of the calculus of probabilities with a view to maintain the horses in a compact group and so as to attribute to the competitors different degrees of expertness.

The invention will be described herein-after with reference to the accompanying drawings, in which:

Fig. 1 shows a plan view of the race course 35 upon which the game will be played;

Figs. 2 to 11 are diagrammatic views representing the installations and accessories used in this game;

Figs. 12 to 19 show the development of the 40 special dice used.

The game will be played upon a game-board of suitable material and which will represent a green whereupon tracks are traced, the design of said tracks being similar 45 to the disposition of actual race courses. Provision will be made for flat races, hurdle races and steeple-chases (see Fig. 1). These tracks are subdivided in small graduations by transversal lines, the compartments being numbered usually from 1 to 150. The tracks are 50 defined by means of lines and bear the impediments usually installed in actual race-grounds. The usual installations of race-grounds are placed in appropriate positions 55 upon the game-board, not only to give at the whole the familiar sight of a race course, but

also to use such details during the competition. Each of these accessories will have its appropriate use. The grand stand illustrated in Fig. 2 will contain the mechanism for throwing the disc used, said throw being operated inside a transparent cage by means of a spring-controlled lever *t*. The "weighing reserved enclosure" illustrated in Fig. 3 acts as a box for the reception of different values such as stakes, percentages, etc. The illustrations of the "betting offices" Fig. 4 are respectively appropriated to receive the amounts of the betting at "winning" or the betting at "placed". To each of these betting 70 establishments is annexed a box containing the tickets to be distributed (Fig. 5).

The hindrances which are dispersed over the track are imitations of the various items which can be seen in actual steeplechases or hurdle-races. Fig. 6 shows, by way of example, one of the impediments used.

On a level with the compartment numbered 150 facing the grand stand, is erected the winning post and the scoring board (Fig. 7), said scoring board bearing numbered compartments wherein the starting horses will be marked with their particular chances, such as "advance points" or "rise points" to which will be referred hereafter, said marking being 85 made by the introduction of plates (Fig. 8) bearing the necessary indications. The plates as also the boards which will give the average point about which the race will be played are stored in a casing illustrated in Fig. 9. 90 Model horses are used, each bearing a number near the saddle (Fig. 10), as also model jockeys having various coloured dressings (Fig. 11), said jockeys being interchangeable for all the horses.

The race-track being divided into numbered compartments, the progressive movement of the competitors is determined by means of dice bearing a special numbering, so as to allow a very large number of combinations and to realize furthermore a constant and compact group of progressing horses. This latter effect cannot be obtained by the use of the ordinary dice. In a throw of three ordinary dice, the lowest number thrown is 100 3 and the highest one 18. Between these maximum and minimum numbers the difference is of 15 points for an average point of: $18 + 3$ or $10\frac{1}{2}$. It is materially impossible in 110 2 these conditions to maintain the competitors in a serrated compact group during the pro-

gression of the race. The dice used in the present game are numbered so as to lower the difference between the extreme throws and to make this difference no more a multiple number but a fraction of the average point.

In the improved indoor race game use will be made of eight dice, as illustrated in Figs. 12 to 19, the special numbering of which allows, when use is made of two dice, to reduce the difference between the extreme throws to 4, and as use is made of three dice at a time, to reduce this difference to 6. If the game is played by means of the combination of the dice Figs. 14, 15 and 16, the average point of these dice is: $4+5+6=15$; the minimum throw is 12 and the maximum throw 18; the difference is only 6 for an average point of 15. If the dice Figs. 17, 18, and 19 will be used in combination, this constant difference of 6 points will be accompanied by an average point of 24. With such dice, which have been coloured in different colours to facilitate the handling, the horses will remain in group during the competition, so as to maintain the same interest in the race, as can be seen in actual horse races.

I am aware that in an indoor game imitating golf use has been made of dice bearing also a numbering adapted to lessen the difference between the maximum and minimum throws, but in such game dice are used in a quite different intention and combination.

Furthermore, by the use of the set of dice as illustrated, spectators can observe, as the race progresses, the chances of each of the competitors, knowing that with three dice selected from said set, it will be possible to have 216 combinations, which can be designed as follows:

If m will denote the average point adopted by the choice of dice: for 216 throws there will be the following possible throws: eight times $m-3$, twenty-four times $m-2$, forty-eight times $m-1$, fifty-six times m , forty-eight times $m+1$, twenty-four times $m+2$, and eight times $m+3$. The chances to bring forth each of the points in the aforesaid succession will be of: $1/27, 3/27, 6/27, 7/27, 6/27, 3/27$ and $1/27$.

It can be stated that the spectator, in a race whereof the distance will be covered by fifteen throws for each competitor, being desirous to calculate the chances of a horse to bring forth a second time the maximum point which he has just marked, must consider said chance as nil, as each competitor has only one chance in twenty-seven to make this point and that he has already marked it once in the series of only fifteen throws. It can be observed also how many chances each competitor has not to divert from the average point (by more than one point), as the chances of $m-1, m$ and $m+1$ give in totali-

zation: $6+7+6$ or 19 for twenty-seven throws. That is to say the $2/3$.

The game could be played by means of any combination of three dice providing for an appropriate average point, as for instance the dice of Figs. 14, 15 and 16, which provide for the average point of 15. But to realize another novel and characteristic feature of the game, namely the possibility to give to each competitor of an indoor race different and variable degrees of expertness, as it is the case in actual horse races, it was necessary to provide for a series of average points remaining at the disposal of the players, because the practical realization of the game necessitates an unvariable number of throws, whatever may be the distance of the race, which may be of a half track or amount to more than two turns over the board. By means of the dice, when a game is played with two dice at a time, there remains at disposal a number of average points going from 5 to 17, this only by suitable combination of the dice. When three dice are used, there are at the disposal average points going from 9 to 24, also in a continuous manner.

If a race is to be played over 150 points which, for reasons which will be explained hereafter, it is desirous to finish in fifteen throws for each competitor, the necessary average point will be 10. If the distance determined is 300 points, the average point should be 20, etc. Thereby it becomes possible to divide the competitors by expertness by very simple means allowing to calculate the chance of each competitor and to present in this way favourites and outsiders.

Assuming that, instead of playing independent parties without connection between each other, some players will form a club having regular meetings and wherein the players will be owners of a fictitious stable whereof the elements are regularly recorded in a stud-book and which will comprise horses of different ages (2, 3, 4, 5, 6 years or more) and adapted for different categories of races (flat, hurdle-races, steeple-chases, etc.). After the first race meeting, the "winning" and "placed" competitors will take benefit of a certain number of "start-off points", which are allowed to them and recorded in the stud-book. In the following meeting these competitors will make use of these "start-off points" which will be added at starting to their first throw of dice. If this number of "start-off points" is lower than the difference possible between the throws, the compact formation of the group will not be disturbed by the allowance of said advantages, but if such number of "start-off points" would be higher than said difference, the interest of the race will be lowered and the imitation of an actual race will not be sufficiently executed. Therefore, as soon as the number

of "start-off points" attains the number of 4, 5 or 6, they are replaced by a "rise point". By a "rise point" is understood a point that is allowed to the competitors each time that the total numbering of their throw will remain inferior to the average point. If we refer to the chances as described herebefore, it can be stated that for a number X of dice throws there are nearly $\frac{1}{3}$, (exactly $10/27$) that remain beneath the average point, whereas $\frac{1}{3}$ remain above the average point and the remaining $7/27$ is equal to said point. Therefore, replacing 4 "start-off points" for instance by one "rise point" necessitates that the race should be ended in twelve dice throws for each horse, as for such twelve throws there are four points beneath the average point, for which the favourite horse will take benefit each time of an additional "rise point". If the "rise point" will be substituted for instance for five "start-off points", this will necessitate that the race should be played in $3 \times 5 = 15$ throws.

The same regulation can be applied for determining the benefit of two "rise points", equivalent in this case to ten "start-off points" for a race of fifteen throws, or of three "rise points" being equivalent to fifteen "start-off points" in the same conditions.

By the creation of the "rise points" there is substituted to the certainty of taking benefit of 5, 10 or 15 "start-off points", the probability (mathematically equal and even somewhat higher) of such benefit. Really, one "rise point" corresponds mathematically to $5\frac{1}{2}$ "start-off points"; two "rise points" to 11 "start-off points"; and three "rise points" to $16\frac{1}{2}$ "start-off points" and in special conditioned races or "handicaps" where the horses take benefit of all or of part of their advantages, the imitation of an actual race will remain perfect, as the influence of "rise points" will only be brought forward as the race progresses, allowing the winning of the favourites at the end of the race only, without, however, firmly ensuring such winning, which eventually would cancel any interest in the game. In handicaps, however, which theoretically in races level the value of the competitors, no advantage will be granted to the horses engaged, but the benefit of their winning will obviously be added to the points previously obtained.

It must be observed that the ordinary game with independent competitions, as described before, can also be applied for all varieties of races. It is sufficient to previously agree for each competitor to have a certain number of "start-off points" or "rise points" to attribute conventionally a value which will afford them less or more advantages.

It must also be observed that, in conformity with actual races, the speed at the end of the race can be accelerated, as each competition can use in succession two or more

average points. Thus, for a race of 150 points in 15 throws, can be substituted to using the single average number 10, three successive average points, as for instance 8 for the five first throws (40 points); 10 for the five following throws (50 points); and 12 for the five last throws (60 points), which brings forth the total of 150 points.

The mechanism of hurdle-races is the same, but here, if the point thrown for a horse will bring this latter in a compartment occupied with an impediment, the horse is considered as having fallen and set out of bound. If the throw brings the horse directly in the compartment following the impediment, there is a fault and a small loss of points.

The hindrances are placed in spots varying according to the length of the race and the average points used, so as to remain out of the probable grouping spots, and which can be predetermined. In a steeple-chase the chances for falling are much greater, the hindrances having then a fixed place independently from the conditions of the race.

Furthermore, slipping accidents want to be added to the ordinary accidents provided in hurdle-races.

Furthermore, in flat races, there is only one accident provided, that is a non-starting. This is produced when a competitor will throw the lowest point and this will be accompanied by a loss of points, so as to considerably lower the chances of this competitor.

To avoid errors and to allow the spectators to follow the events of the race, the scoring board will indicate for each competitor the number of his "start-off points" and that of his "rise points".

I claim:

1. Apparatus for playing dice controlled horse race game, comprising in combination: playing pieces representing horses, a divided and numbered chart representing a race course, reproductions on a smaller scale of the installations and accessories used in actual horse-races, each of such elements being affected to an operation in the combination of the game, a set of numbered dice controlling the progressive movement of the playing members, said set comprising a series of dice the lower numerals of which differ by 1 each from another, so as to allow providing of different average points.

2. Apparatus for playing dice controlled horse race game, comprising in combination: playing pieces representing horses, a divided and numbered chart representing a race course, reproductions on a smaller scale of the installations and accessories used in actual horse-races, each of such elements being affected to an operation in the combination of the game, a set of numbered dice controlling the progressive movement of the playing members, said set comprising a series of

dice the lower numerals of which differ by one each from another, the numbering being such that the differences between the maximum and minimum numerals of the same die is equal to 2, with a view of maintaining the competitors in a compact group during their movement.

3. Apparatus for playing dice controlled horse race game, comprising in combination: 10 playing pieces representing horses, a divided and numbered chart representing a race course, reproductions on a smaller scale of the installations and accessories used in actual horse-races, each of such elements being

affected to an operation in the combination of the game, a set of numbered dice controlling the progressive movement of the playing members, said set comprising a series of dice, the lower numerals of which differ by 1 each from another, the numbering being such that the difference between the maximum and minimum numerals of the same dice is equal to 2, substantially as described.

In testimony whereof I signed hereunto 25 my name.

LÉON M. E. ROTTENBURG.
